(57) CLAIM

The ornamental designs for a sleeping bag, as shown and described.

DESCRIPTION

FIG. 1 is a perspective view of a sleeping bag of our new design.

FIG. 2 is a front elevation thereof.

FIG. 3 is a rear elevation thereof.

FIG. 4 is a right side elevation thereof.

FIG. 5 is a left side elevation thereof.

FIG. 6 is a top plan view thereof; and,

FIG. 7 is a bottom plan view thereof.

The broken lines present in the figures are included for the purpose of illustrating portions of the article that form no part of the claimed design.
